DESIGN FOR A COMBINED BOUDOIR LAMP AND JEWEL CASE

Ernest M. Barry, Maywood, Calif.

Application January 3, 1944, Serial No. 112,152

Term of patent 14 years

(Cl. D48—20)

To all whom it may concern:

Be it known that I, Ernest M. Barry, a citizen of the United States, residing at Maywood, in the county of Los Angeles and State of California, have invented a new, original, and ornamental Design for a Combined Boudoir Lamp and Jewel Case, of which the following is a specification, reference being had to the accompanying drawing forming part thereof.

Fig. 1 is a perspective view of a combined boudoir lamp and jewel case embodying my new design.

Fig. 2 is an exploded view.

I claim:

The ornamental design for a combined boudoir lamp and jewel case, substantially as shown.

ERNEST M. BARRY.
